UNITED STATES PATENT OFFICE.

SAMUEL H. CAWLEY, OF EL DORADO, OHIO.

SULKY-HARROW.

SPECIFICATION forming part of Letters Patent No. 289,616, dated December 4, 1883.

Application filed July 28, 1883. (No model.)

To all whom it may concern:

Be it known that I, SAMUEL H. CAWLEY, a citizen of the United States, residing at El Dorado, in the county of Preble and State of Ohio, have invented certain new and useful Improvements in Sulky-Harrows; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to harrows, and more particularly to that class known as "wheel" or "sulky" harrows, the object being to provide means for raising the harrow from the ground when not in use.

A further object of the invention is to provide a harrow which may be so constructed and arranged as to be operated forward or backward.

The invention consists in the improved construction and combinations of parts hereinafter fully described, and pointed out in the claims.

In the drawings, Figure 1 is a perspective view of my improved harrow. Fig. 2 is a plan view of the same, and Figs. 3 and 4 are detached views.

30 A A' represent the harrow-sections, the beams of which are secured together at their rear and forward ends by rods or braces a a', and provided at their front and rear ends with hooks a' a'', for the attachment of the sulky-frame.

35 B B' represent the wheels of the harrow-sulky, loosely mounted upon an axle, b, and adapted to run between the beams of the harrow. Upon the axle b, and at about the center 40 of said axle, is rigidly mounted a disk-lever, b', which is connected to the draft-tongue C by a depending loop, c'.

45 D D' represent plates secured to the beams of the harrow, their inner sides being bent at right angles to the plate, and provided with perforations d d', for the attachment of slotted arms d'', which are attached at their other ends to the disk b'. To the draft-tongue C is secured a perforated bar, d'', which is adapted 50 to receive a pin or stop, d'', which holds the harrow above the ground when not in use.

E represents the seat, which is mounted on a bar, e, secured at one end to the under side of the seat and at the other end to the draft-tongue C.

55 e' e'' represent braces for the seat, which connect with the crank-arms e' e''. By this arrangement the weight of the operator, in a measure, overcomes the weight of the harrow in lifting the same. The crank-arms e' e'' are secured at one end to the axle b, and loosely secured at their other ends to the outer beams, e' e'', of the sulky-frame.

F represents a lever rigidly mounted on the axle b, and adapted to raise or lower the harrow-frames, as desired.

65 f f' represent plates secured to the beams near the outer sides of the harrow-frames, and perforated, as shown, for the attachment of a slotted arm, f'', which is pivotally secured to the crank-arm f''. The crank-arm f'' is rigidly mounted on the shaft b.

70 G represents the sulky-frame, consisting of the bars g g', which are pivotally secured to the crank-arms e' e'', said bars being secured between the horizontal bars H H'. The bars g g' are braced by a horizontal rod or bar, h'', and two diagonal bars h' h''.

I represents a bail or loop bent around the draft-tongue C, the ends being secured to the horizontal bars H H'.

J J represent a series of diagonal slats connected to hooks, which are secured to the ends of the harrow-beams and pivoted between the horizontal bars H H'. By the use of the slats 85 J J the harrow-frames will adapt themselves to uneven surfaces without interfering with the sulky.

It will be apparent by the construction shown and described that by detaching the slats J J 90 and the crank-arms the sulky-frame may be reversed and secured at the rear ends of the harrow-frames.

It will also be seen that the construction affords a ready means for raising the harrow-frames from the ground when not in use.

When it is desired to raise the harrow, the lever F is thrown forward, thus turning the axle b and raising its crank-arms f'', which latter are connected by the links f''' to the harrow-plates f f'. The disk b' also assists the raising of the harrow through the medium of

the links d^2 , which latter are connected to the central plates, D, of the harrow.

Having fully described my invention, what I claim as new, and desire to secure by Letters 5 Patent, is—

1. In a harrow, the combination, with the sections A A', of an axle having wheels mounted thereon and provided with arms for its attachment to the harrow-sections, and a disk 10 rigidly mounted on said axle, the draft-tongue C, secured to the disk by a depending loop, a bar mounted on said draft-tongue, at the rear end of which is secured a seat, and braces secured to the under side of the seat and connecting with the crank-arms $e^3 e^4$, substantially as set forth.

2. In a harrow, the combination, with the sections A A', the beams of which are provided with plates for the attachment of slotted 20 arms which are pivotally secured at their other ends to crank-arms rigidly secured at the ends of the axle, and a disk rigidly mounted on the

axle, of a tongue-bar secured to said disk by a depending loop, a bar, e, upon which is secured a seat, and which is provided with a 25 slot adapted to receive a perforated plate secured to the tongue-bar, and a pin adapted to fit the perforations of said plate, substantially as set forth.

3. In a harrow, the combination, with the 30 axle and the sulky-frame, consisting of the bars g g', pivotally secured to the crank-arms $e^3 e^4$, the bars h^2, h^3 , and h^4 , and the horizontal bars H H', having a bail secured to the tongue-bar C, of a series of crossed slats pivoted between the bars H H', and connected to the 35 beams of the harrow by hooks or other analogous means, substantially as set forth.

In testimony whereof I affix my signature in presence of two witnesses.

SAMUEL H. CAWLEY.
